UNITED STATES PATENT OFFICE

JULIUS A. SEIDEL, OF ST. LOUIS, MISSOURI, ASSIGNOR TO JULIUS SEIDEL LUMBER COMPANY, OF ST. LOUIS, MISSOURI, A CORPORATION OF MISSOURI

DESIGN FOR A CHAIR SETTEE

Application filed May 11, 1931. Serial No. 39,812. Term of patent 14 years.

To all whom it may concern:

Be it known that I, JULIUS A. SEIDEL, a citizen of the United States of America, residing at the city of St. Louis, State of Missouri, have invented a new, original, and ornamental Design for a Chair Settee, of which the following is a specification, reference being had to the accompanying drawings, forming a part thereof.

In the drawings Figure 1 is a front elevational view; Figure 2 a side view; and Figure 3 a rear elevational view, showing my new design.

I claim:

The ornamental design for a chair settee, as shown.

JULIUS A. SEIDEL.
